UNITED STATES PATENT OFFICE.

ELI E. PENTER, OF DETROIT, MICHIGAN, ASSIGNOR OF ONE-FIFTH TO CHARLES K. SEIBERT, OF DETROIT, MICHIGAN.

INTERNAL-COMBUSTION ENGINE.

1,377,789.

Specification of Letters Patent. Patented May 10, 1921.

Application filed April 18, 1917. Serial No. 162,984.

To all whom it may concern:

Be it known that I, ELI E. PENTER, a citizen of the United States of America, residing at Detroit, in the county of Wayne and State of Michigan, have invented certain new and useful Improvements in Internal-Combustion Engines, of which the following is a specification, reference being had therein to the accompanying drawings.

10 The invention relates to internal combustion engines and comprises the novel cycle and novel construction as hereinafter set forth. It is the primary object of the invention to obtain great flexibility, maintenance 15 of uniform combustion conditions throughout the power range of the engine and under varying loads and speeds, high efficiency and high power with a simple construction, which dispenses with many parts usually 20 necessary and which is easily manufactured at low cost. More specifically, the invention has among its objects the accurate metering of the air and fuel forming the combustible mixture, the maintenance of uniform com- 25 pression under varying loads, the introduction of a uniform weight of air into the engine cylinder during each cycle and the separation of a portion of the air so introduced for mixing with the fuel, maintain- 30 ing the separation during explosion and the working stroke. A further feature is the thorough scavenging of the products of combustion from the cylinder and the utilization of the air not required for the com- 35 bustible mixture as a resilient cushion, absorbing a portion of the initial impulse and delivering its power later in the working stroke.

In structure my invention comprises es- 40 sentially a cylinder, a piston therein and a movable or floating piston, together with means for introducing a fixed weight of air on one side of the latter piston and transferring a variable portion thereof to the op- 45 posite side for commingling with the fuel. My invention also has reference to various other specific structural features as herein- after set forth.

In the drawings:

50 Figure 1 is a central longitudinal section through an engine embodying my invention; and

Figs. 2 to 11 are diagrams showing suc- 55 cessive positions during the cycle.

As shown, A is the cylinder, B the piston

therein, C the connecting rod, D the crank and E the crank-casing. The cylinder A contains in addition to the piston B a floating piston F which is movable independently of the piston B and from a position in 60 substantial contact therewith to various positions within the cylinder. The inlet for the air is on the opposite side of the floating piston from the piston and is preferably controlled by an automatic valve G. There is 65 also provided a by-pass or transfer passage H which in certain positions of the floating piston permits of the transference of a portion of the air into the space between the floating piston and piston. As specifically 70 shown, the floating piston forms the valve controlling this by-pass, being provided with a shell portion I which co-operates with ports J and K opening into the cylinder. The shell I is of greater length on one side than 75 the other, so that by rotatively adjusting the floating piston the cut-off of the port J may be varied.

The fuel is introduced into the cylinder in measured quantities proportionate to the 80 quantity of air transferred through the by- 85 pass H, and is preferably commingled with the air during its transfer. Any suitable means may be employed for metering and introducing the fuel into the passage H, but 90 as shown L is a chamber containing the liquid fuel, M is a rod extending through the chamber L and into the passage H, and N is a sleeve on a reduced portion O of the rod M with its outer face flush with the 95 larger diameter of said rod, said sleeve being slidable on the portion O with a limited lost-motion. The arrangement is such that an annular space P between the end of the sleeve and the shoulder Q of the rod when 100 in the chamber L will be filled with the liquid fuel and during the upward move- 105 ment of the rod, which is actuated by suitable drive connections with the engine, will be carried into the passage H, while on the downward movement of the rod the liquid fuel will be ejected by the temporary delay in movement of the sleeve N until the lost-motion is taken up. The lever N' threadedly engages the portion O of the rod M and 110 abuts against the sleeve N for varying the amount of lost-motion, to thereby vary the quantity of liquid fuel introduced into the passage H and proportioning it to the quantity of air transferred. The cylinder A is 110

provided with exhaust ports R which are uncovered at the end of the movement of the piston, and an auxiliary exhaust port S is controlled by a mechanically-actuated and 5 timed valve T, preferably carried by the rod M. There is also provided means for placing a differential pressure upon the opposite faces of said floating piston when the pressure of the gases in contact therewith are 10 substantially equal, so that the floating piston will be caused to move away from the piston. As shown, this means comprises a small cylinder V in alinement with the cylinder A and containing a piston W which is 15 connected by a rod X to the floating piston F. The cylinder V is connected by a conduit Y with the conduit U so that the pressure within said cylinder is equal to the pressure at which air is admitted to the cylinder A. 20

With the construction as thus far described, the operation is as follows: The air which is introduced into the cylinder is preferably at more than atmospheric pressure and is derived from any suitable source 25 of supply, such as the conduit U connected to the inlet passage controlled by the valve G. Assuming the parts are in the position shown in Fig. 2, the piston B is in a position 30 upon its upward stroke where the main exhaust ports and auxiliary exhaust ports S are covered and the floating piston F is in substantial contact with the upper end of the piston. The automatic valve G is also open, 35 and it may be assumed that the air from the conduit U at a predetermined pressure, such for instance as fifteen pounds above atmospheric, fills the cylinder above the floating piston. During the continued upward 40 stroke of the piston the air within the cylinder will be further compressed, closing the valve G, as shown in Fig. 3, and the compression will continue until the piston and floating piston reach the point shown in 45 Fig. 4. Here the port K is in communication with the space between the piston and floating piston, permitting access of the highly-compressed air to the lower face of the floating piston and thereby balancing 50 the pressure upon opposite sides of said floating piston. When this is accomplished the pressure exerted upon the piston W by the air within the cylinder V will move the floating piston upward away from 55 the piston B, as shown in Fig. 5, thereby causing the air to flow around through the by-pass H and during its passage to pick up the liquid fuel to form an explosive mixture. This will continue until 60 the shell I of the floating piston cuts off the port H, preventing further transfer and separating the chamber above the floating piston from that below, as shown in Fig. 6. The explosive charge is then ignited, as indicated in Fig. 7, and the pressure developed 65

in the explosion chamber will cause the further upward movement of the floating piston F, increasing the pressure of the air above the floating piston while the pressure below is decreasing due to expansion until 70 the two pressures are equal, the floating piston being in the position indicated in Fig. 8. At the same time the piston begins its working stroke and as the pressure within the explosion chamber is decreased by expansion, 75 the floating piston will be moved downward so that the power stored in its upward movement will be given back during the working stroke. Furthermore, the heat of explosion which passes through the floating piston will 80 be communicated to the compressed air thereabove and will be utilized in further expanding the air. When the piston reaches a point for opening the exhaust ports R, as indicated in Fig. 9, the pressure below the 85 floating piston will rapidly drop and the pressure above will cause a movement of said floating piston toward the piston. This will continue until the exhaust ports R are fully opened (Fig. 10) and are again sealed 90 by the upward movement of the piston, at which time the auxiliary exhaust port S is opened by the valve T to permit the further exhaustion of the remaining gases between the floating piston and piston, as shown in 95 Fig. 11. There will, however, remain a sufficient amount of gas between these members to form a cushion, preventing any sudden impact of the one upon the other but permitting them to move into close proximity, as indicated in Fig. 2, which completes the cycle. 100

It will be obvious that the power may be varied by changing the point of cut-off so that a larger or smaller amount of air is 105 transferred through the by-pass H and by correspondingly varying the quantity of fuel introduced into the by-pass. It is also possible to vary the pressure at which the air is admitted to the cylinder, and as the 110 pressure of the air within the cylinder above the floating piston is always higher than atmospheric, the combustion gases may be exhausted at a higher than atmospheric pressure and may be utilized for developing 115 further power through any suitable mechanism (not shown).

From the above description it will be readily seen that I have provided a construction of engine in which the weights of 120 air and fuel can be accurately measured; in which the cylinder is mechanically cleared of burned gases by means of the floating piston; and in which the by-pass for transferring the air from the back to the front 125 side of the floating piston may be used as a mixing chamber and the fuel fed into this mixing chamber after the air has been heated by compression. Furthermore, an almost ideal shape for the combustion chamber is 130

provided, since the combustion takes place in the space between the piston and the floating piston. A portion of the heat of combustion is transferred to the air upon the 5 opposite side of the floating piston and is utilized during the expansion stroke and this air also acts as a cushion to absorb the hammer-like blow of the explosion, thereby relieving the working parts of the excessive 10 strains, due to the peak pressures.

What I claim as my invention is:

1. In an internal combustion engine, the combination with a cylinder, of a piston and a separately-movable piston therein, means 15 for introducing air into said cylinder when said separately movable piston is adjacent to said piston and for compressing the air by the joint movement of said pistons, means for simultaneously separating said separately movable piston from said piston and transferring a portion of the compressed air to the space between the same, and means for introducing fuel with the transferred air and igniting the same, the force of explosion 20 moving said separately movable piston to further compress the air to an equal pressure, and the pressure of both the air and combustion gases reacting upon the first-mentioned piston in the working stroke. 25

30 2. In an internal combustion engine, the combination with a cylinder, a piston and a separately-movable piston therein, of means for introducing air into said cylinder while said last-mentioned piston is adjacent to said first-mentioned piston and for compressing the air by the joint movement of said pistons, means for simultaneously separating said separately-movable piston from said first-mentioned piston and transferring 35 a portion of the compressed air to the space therebetween, means for introducing fuel with the transferred air and igniting the same, the force of explosion reacting upon the separately-movable piston to compress 40 the air on the opposite side thereof until the pressures above and below said piston are equalized and the expansion of both the air and combustion gases being utilized in the working stroke, and means for exhausting 45 the products of explosion to permit the approach of the pistons, a portion of the 50 exhaust being trapped to form a cushion.

3. In an internal combustion engine, the combination with a cylinder, a piston and a separately-movable piston therein, of means for introducing air into said cylinder while said last-mentioned piston is adjacent to said first-mentioned piston and for compressing the air by the joint movement 55 of said pistons, means for simultaneously separating said pistons and transferring a portion of the compressed air to the space therebetween, means for introducing fuel into the transferred air and igniting the 60 same, the force of explosion reacting upon 65

said separately-movable piston to equalize the pressure of air and gas, both operating expansively during the working stroke, ports uncovered by the movement of the piston to exhaust the products of explosion, 70 and an auxiliary exhaust operating during the return stroke of the piston for permitting the same to approach said separately-movable piston, a cushion of gas being maintained therebetween. 75

4. In an internal combustion engine, the combination with a cylinder, a piston and a separately-movable piston therein, of means for introducing air into said cylinder while said separately-movable piston is adjacent 80 to said piston and for compressing the air by the joint movement of said piston and separately-movable piston, means for simultaneously separating said pistons and for transferring a portion of the compressed air 85 to the space therebetween, means for introducing fuel into the transfer passage proportionate to the quantity of air transferred, means for igniting the explosive mixture, the force of explosion reacting upon said 90 separately-movable piston compressing the air thereabove to the point of equalization with the gas therebeneath, and both air and gas operating expansively during the working stroke, and means for exhausting the 95 products of combustion to permit the re-approach of said pistons and the scavenging of the cylinder thereby.

5. In an internal combustion engine, the combination with a cylinder, a piston and a floating piston therein, of means for introducing air into said cylinder at more than atmospheric pressure and while said floating piston is adjacent to said first mentioned piston, the air thus introduced being further compressed by the joint movement of said pistons, means for simultaneously separating said pistons and transferring a variable portion of the compressed air to the space therebetween, means for commingling with the transferred air a proportionate quantity of fuel, means for igniting the explosive mixture, the force of explosion reacting upon said floating piston and air-cushion to equalize the pressure of air and combustion gases, both operating expansively during the working stroke of the first mentioned piston, means for exhausting the products of combustion to drop the pressure thereof to less than the introduction 100 pressure of air, and an automatic valve permitting the admission of air and the movement of the floating piston thereby again into adjacency to the first-mentioned piston. 105

6. In an internal combustion engine, the combination with a cylinder, of a main piston and a floating piston in said cylinder, said floating piston being movable independently of said main piston, means for introducing air into said cylinder when said 110 115 120 125 130

floating piston is adjacent to said main piston near the end of the power stroke, a by-pass provided with ports separated longitudinally of said cylinder and connecting into 5 the wall thereof, said floating piston adapted to close each of said ports, and means for introducing fuel into said by-pass.

7. In an internal combustion engine, the combination with a cylinder, of a main piston 10 ton and a floating piston in said cylinder, means for introducing air into said cylin-

der, a by-pass provided with ports separated longitudinally of said cylinder and opening into the wall thereof, said floating piston adapted to close said ports, means rotatably 15 adjusting said floating piston to vary the time of opening and closing one of said ports, and means for introducing fuel into said by-pass.

In testimony whereof I affix my signature. 20

ELI E. PENTER.
